UNITED STATES PATENT OFFICE.

EMIL PODLESAK AND BRUCE R. BECKWITH, OF RACINE, WISCONSIN, ASSIGNEES TO
WEBSTER ELECTRIC COMPANY, OF RACINE, WISCONSIN, A CORPORATION OF WEST
VIRGINIA.

MAGNETO-MACHINE.

1,180,426.

Specification of Letters Patent. Patented Apr. 25, 1916.

Application filed May 7, 1915. Serial No. 26,527.

To all whom it may concern:

Be it known that we, EMIL PODLESAK and BRUCE R. BECKWITH, citizens of the United States, residing in Racine, in the county of Racine and State of Wisconsin, have invented certain new and useful Improvements in Magneto-Machines, of which the following is a full, clear, concise, and exact description, reference being had to the accompanying drawings, forming a part of this specification.

Our invention relates to magneto machines, particularly current generators for ignition purposes, and the object of our invention is to provide a highly efficient and compact machine of this class that can be economically manufactured.

The embodiment of our invention herein-after described is, among other things, characterized by the fact that all of the several working parts thereof are readily accessible for inspection or repair whenever this becomes desirable.

These and other features of our improved magneto machines are fully set forth in the following description in which reference is made to the accompanying drawings in which,

Figure 1 is a front elevational view of our improved magneto machine. Fig. 2 is a horizontal sectional view thereof. Fig. 3 is a vertical sectional view thereof, the rotor being shown out of its normal position for the sake of clearness in illustration. Fig. 4 is a vertical sectional view taken on the line 4-4 of Fig. 3. Fig. 5 is a front elevational view illustrating how the rotor and its associated parts may readily be removed to afford access to the pole pieces and generating windings carried thereby. Fig. 6 is an isolated detailed view of the rotor and associated parts after the same have been removed from the machine. Fig. 7 is an isolated front elevational view of one of the removable side plates forming a part of the magneto machine of our invention; and Fig. 8 is an end view thereof.

Similar characters of reference refer to similar parts throughout the several views. Referring to the drawings, it will be seen that our present machine comprises a pair of pole pieces 10-10, each of which is provided with three polar projections. Each of the pole pieces 10-10 comprises a plurality of

laminated, substantially E-shaped stampings, and the several stampings constituting the pole pieces are retained in proper position and the pole pieces are retained in proper position by pins 11-11 which rigidly connect the pole pieces with the non-magnetic side plates 12-12, each of which has a relatively large opening 12^a therein, as is most clearly illustrated in Fig. 5. The several pins 11-11 are riveted at their ends in a manner well-known to the art and thus the plates 12-12 and the pole pieces 10-10 are permanently and rigidly connected. The pole pieces 10-10 are provided with steps upon which rest the lower ends of permanent magnets 13-13, as best illustrated in Fig. 1, the said magnets being conveniently disposed one within the other, as illustrated. Passing over the magnets 13-13 is a sheet metal strip, or band, 14, which extends down under the pole pieces 10 and is interlocked with a sheet metal bottom plate 15, as is clearly illustrated in Fig. 3. In addition to being connected to the lower ends of the band 14 the sheet metal bottom plate 16 may be retained in position by screws 16, or otherwise. The band 14, in addition to in part supporting the bottom plate 16, may be utilized as a name plate. We find that this arrangement lends a generally neat appearance to the completed machine.

At 17-17 we have illustrated end plates, each of which is secured to the permanent side plates 12-12 by a plurality of screws 13-13. Each of the end plates 17 is desirably provided with a set screw 18, which set screw when tightened up serves securely to retain the permanent magnets in proper position upon the magneto pole pieces. Each of the end plates 17 is, moreover, provided with a forwardly and horizontally extending arm 17^a, the function of which arms will presently be made apparent.

The permanent side plates 12-12 are illustrated as provided with downwardly extending threaded studs or bolts 19-19 by means of which the magneto machine may be securely mounted upon a bracket, illustrated at 20 in Fig. 1. Our present invention is not particularly concerned with this bracket and we have, therefore, not illustrated the same in detail, and it will be sufficient to state that this bracket may con-

veniently be similar to the bracket illustrated in Reissue Patent No. 18,878, granted to Emil Podlesak on February 9, 1915.

Disposed upon the pole pieces 10 and located between the permanent side plates 12 is a plate 21 of non-magnetic and non-conductive material which, as illustrated, may conveniently carry a terminal block at 22.

At 23 we have illustrated a cap, which 10 in combination with the upper ends of the permanent side plates 12-12, constitutes a housing for the several instrumentalities supported by the plate 21.

At 24-24 we have illustrated the generating windings of our improved magneto machine, each of which generating windings is disposed upon the middle polar projection of one of the laminated pole pieces 10. The generating windings which are electrically 20 connected in series are solely retained in proper position with respect to their associated pole pieces by friction and by means presently to be explained.

At 25 and 26 we have illustrated removable side plates adapted to be secured to the permanent side plates 12 by screws 27-27. It will be noted that each of these removable side plates is provided with a more or less annular flange on its inner face, which flange 30 extends through the aperture 12^a in the associated permanent side plate 12 and is disposed adjacent the generating windings 24-24. It will thus be seen that when the removable side plates 25 and 26 are in the 35 positions illustrated in Figs. 1 and 2 of the drawings, the inwardly extending flanges of the removable side plates 25 and 26, illustrated respectively at 25^a and 26^a, effectually serve to retain the generating windings 24 in 40 proper position and to prevent displacement thereof. Each of the removable side plates, 25, 26, is moreover provided on its inner surface with a pair of depressions, most clearly illustrated at 28 in Fig. 7 of the drawings, 45 these depressions serving to receive the adjacent ends of the generating windings 24 when the side plates are in proper position, as illustrated in Fig. 1. The removable side plates 25 and 26 moreover provide bearings 50 for a shaft 29, which shaft carries a rotor 30 of laminated material and which rotor has four radial arms and substantially the cross section of a Maltese cross.

It is to be understood that when the rotor 55 30 is oscillated in proximity to the polar projections of the pole pieces 10-10 the rapid change of magnetic lines through the generating windings induces an electric current in the windings. It will not be necessary for us to describe the co-operation of the 60 rotor or inductor with the projections of the pole pieces 10-10, inasmuch as the Patent No. 1,098,052, granted to Emil Podlesak on May 26, 1914, illustrates and describes in detail a magneto machine comprising substan-

tially E shaped pole pieces and a laminated inductor having four radial arms. Our present invention is not particularly concerned with the details of the rotor and pole pieces, but is rather directed to the several 70 features set forth in the claims appended to this specification.

The removable side plates 25 and 26 are desirably provided with receptacles for oiled felt or other suitable material for properly 75 lubricating the shaft bearings, these devices being illustrated most clearly in Fig. 4.

Keyed upon the end of the shaft 29 adjacent the removable cover plate 25 is a yoke 31 normally retained in a horizontal position by helical springs 32-32 interposed between the arms of the yoke 31 and the projecting end 17^a of the end plate 17. In this respect our present magneto machine does not materially differ from the devices 85 illustrated in the patents to Emil Podlesak previously referred to.

The end of the shaft 29, adjacent the removable cover plate 26^a, has keyed thereon a collar provided with an integral trip finger 90 33 and a tail piece 34. These parts are not essentially different from the corresponding devices illustrated in reissue patent to Emil Podlesak, hereinbefore referred to, and for the purposes of the present specification it 95 will suffice to say that the trip finger 33 is adapted to be engaged by an engine driven actuator to actuate the inductor against the tension of its associated springs 32, and that the tail piece 34 serves to operate the make 100 and break electrodes (not shown) after the inductor has been moved by the engine driven actuator and released. The Podlesak reissue patent illustrates in detail how the trip finger 33 is actuated by the engine 105 driven actuator and how the tail piece 34 effects operation of the make and break electrodes, so for the purposes of this specification it will not be desirable for us to explain the construction and mode of operation of 110 these parts in detail.

From the foregoing description it will be seen that the laminated pole pieces are rigidly and permanently carried with the permanent side plates 12-12 and that the removable side plates 25 and 26, which provide bearings for the inductor shaft, effectually serve to retain the generating windings 24-24 in proper position. When it becomes necessary or desirable to obtain access to the 120 generating windings or the polar projections the inductor may be withdrawn from operative position between the pole pieces by simply removing the springs 32-32 and the collar, which provides the trip finger 33 and the tail piece 34, from the inductor shaft and unscrewing the side plate 25. The several parts illustrated in Fig. 6 may then be drawn away from the other parts of the magneto machine. Access to the generating 125 130

windings and associated parts is thus had, as is clearly illustrated in Fig. 5 of the drawings. Other advantages of our herein described magneto machine will be apparent to those skilled in the art to which our invention relates.

Having thus described our invention what we claim as new and desire to secure by Letters Patent of the United States is:

- 10 1. A magneto machine comprising in combination with a pair of oppositely disposed pole pieces a pair of permanent side plates carried with said pole pieces, each of said permanent side plates having a central aperture therein, generating windings carried by the pole pieces, a pair of removable side plates, one associated with each of said permanent side plates, flanges carried by said removable side plates extending into the 15 apertures in the permanent side plates to retain the generating windings in position upon their respective pole pieces, and a rotor having bearings in said removable side plates.
- 20 2. A magneto machine comprising in combination a pair of oppositely disposed substantially E-shaped pole pieces, a pair of permanent side plates carried with said pole pieces, a generating winding disposed upon the middle arm of each of said E-shaped

pole pieces, an inductor movable in proximity to said pole pieces, a pair of removable side plates affording bearings for said inductor, and means carried on the inner face of said removable side plates, conformed and disposed to retain said generating winding in position upon its associated pole piece. 35

3. In combination, a pair of substantially E-shaped pole pieces, a pair of permanent side plates carried with said pole pieces, each 40 of said permanent side plates provided with a central aperture, a generating winding disposed upon the middle projection of each of said pole pieces, an inductor movable in proximity to said pole pieces, a pair of removable side plates affording bearings for said inductor, and projections on the inner faces of said removable side plates extending into the apertures in said permanent side plates to retain the generating winding 45 50 in position upon its associated pole piece.

In witness whereof, we hereunto subscribe our names, in the presence of two witnesses, this 27th day of April, A. D. 1915.

EMIL PODLESAK.
BRUCE R. BECKWITH.
